UNITED STATES PATENT OFFICE

ALBERT B. CLISSON, OF SYRACUSE, NEW YORK, ASSIGNOR TO THE PROSPERITY COMPANY, INC., OF SYRACUSE, NEW YORK, A CORPORATION OF NEW YORK

WORKHOLDER FOR PRESSING MACHINES

Application filed April 29, 1926, Serial No. 105,419. Renewed August 29, 1929.

This invention relates to pressing machines particularly machines for pressing articles as shirts, especially where it is necessary when ironing the front of the shirt or other work to stretch the same and hold it in its 5 stretched position by pulling and holding the tail of the shirt.

The invention has for its object a particularly simple and efficient work or tail holder to clamp the shirt tail in stretched position 10 and hold it until the ironing head closes down on the shirt.

The invention consists in the novel features and in the combinations and constructions hereinafter set forth and claimed.

15 In describing this invention reference is had to the accompanying drawings and to the combinations and constructions herein-after set forth and claimed.

20 Figure 1 is a side elevation of a tail holder embodying my invention showing the same applied to one form of standard pressing machine.

Figure 2 is an elevation of this tail holder looking to the right in Figure 1.

25 Figure 3 is a fragmentary view of the frame of the machine, showing the cam for depressing the tail holder.

Figure 4 is a perspective view of the detached work or tail holder.

30 This tail or work holder comprises a carrier mounted on the frame of the pressing machine to have movement into and out of operative position relatively to the buck, the carrier including a flexible member as a tape 35 which is carried by such movement into and out of position over the face of the buck of the machine, the carrier also preferably having a vertical movement when the tape is over the buck, and means for effecting the vertical 40 movement of the carrier to carry the tape toward the buck when the tape is in operative position and to move the tape away from the buck during the initial part of the opening 45 movement of the carrier or tail holder. The vertical movement is such that the tape moves away from the tail of the shirt and also applies itself to the tail of the shirt so as not to wrinkle the tail of the shirt. Some of these 50 features may be omitted.

1 designates the lower pressing element or buck of an ironing or pressing machine, 2 the head which is movable toward and from the buck the former being here shown as mounted upon a goose neck 3 which in turn is mounted upon the table 4 forming part of the frame 5 of the machine; and the head is carried at the front end of a yoke or lever 6 pivoted at 7 between its ends to an upright 8, rising from the frame or the rear leg thereof. The lever 6 is actuated through any suitable means here shown as a toggle including links 9, 10, the link 9 being pivoted at 11 to the rear arm of the yoke 6 and the link 10 being pivoted in any suitable manner to the frame and actuated in any well known manner. The actuation of the head 2 forms no part of this invention and is so far as this tail holding means is concerned the head may be operated in any manner, either by the operator or by motor means. The tail holder 10 comprises a carrier which is here shown as pivotally connected to the frame to swing into and out of operative position and also to move vertically, and a flexible member as a metal tape arranged to be moved into and out of position across the face of the buck. 15

The carrier as here shown is mounted to swing forwardly and rearwardly and comprises front and rear carrier-frame arms 16 and 17 pivoted at 18 in a bearing 19 at one end of a compound-motion support to be presently described. The bearing 19 may be located below the buck and the arms 16 and 17 diverge upwardly from its axis, the rear arm being arranged in the rear of the buck and the front arm having a vertical portion arranged to clear the end of the buck, and a horizontal portion 20 movable over the face of the buck during a forward and rearward movement of the carrier. 21 is the flexible member or metal tape connected at its front end to the horizontal portion 20 and at its rear end to the arm 17. 25

The support for the carrier is here shown as an arm 22 pivoted at one end at 23 to the frame and carrying the bearing 19 at its other end, the lever being movable downwardly against the action of a returning spring 24. The arm 22 carries the compound-motion 30

bearing 19 capable of vertical and rotary motion.

Means is provided for moving the carrier vertically and also for swinging the tape 21 toward and from the buck or the work thereon in order to hold or clamp the work on the buck or to release the work. This means is here shown as a cam 25 formed under the table 4 and a follower or roller 26 on one arm, 10 as the rear arm 17 of the carrier, the follower coacting with the cam. The cam has an abrupt lift to quickly move the carrier vertically down against the tension of the spring 24 and to let the carrier rise abruptly to carry 15 the tape off the work during the initial part of the rearwardly, swinging movement of the carrier frame 16-17. The cam 25 is also provided with a seat 27 arranged to receive the follower, which is a roller, when the carrier 20 has completed its vertical movement toward the buck. The rearward movement of the carrier is limited by a stop 17^a on the frame.

In operation after the shirt has been placed 25 on the buck and the tail pulled to stretch the shirt front on the buck, the carrier 16 is pulled forwardly by hand thus moving the tape 21 over the buck and the work thereon, the tape or band 21 being spaced apart from 30 the work until the follower 26 rides down the abrupt cam 25, such movement bringing the tape 21 squarely down onto the work on the buck without wrinkling the work. The press head 2 is then brought down to press the work 35 and then caused to rise to open the press. The operator then pushes rearwardly on the carrier, first causing it to rise vertically and carry the tape 21 off the work and then rearwardly out of the way.

40 The example of construction shown is to disclose the principle of the invention wherein a clamp tape or band 21 is carried on a suitable frame 16-17 which swings said tape back and forth over the end of the buck and 45 up and down in relation to the work. The pivot 18 may be placed at any convenient position on the frame 4-8 of the ironing press. In the position shown under the iron jaws 1 and 2, the carrier-frame 16-17 quickly 50 swings the clamp tape 21 over the right-hand end of the lower press jaw 1, clearing and not wrinkling the shirt or other work thereon smoothed out in ironing position by the operator, and then the tape or band 21 55 goes down on the work and buck to hold the work in smoothed stretched-out condition so the operator may remove his hands and bring the ironing head down on the work to iron or press it.

60 The radius arm 22 is merely one example of pivot means to attain the vertical action of the clamp band 21; and the illustrated embodiment of the invention portrays a carrier frame 16-17 having its upper ends 65 spaced apart a distance greater than the

width of the buck, so that the band 21 may be longer than the width of the buck. The frame 16-17 is so arranged as to never interfere with the work on the buck and merely swings the clamp band into and out of work-holding position. It is significant that the carrier frame 16-17 swings under the buck 70 1 and squeezes the clamp band 21 over and down onto the work resting on the buck awaiting the ironing operation and that the band 21 is in a position substantially transverse to the buck when ready for the press head to descend to ironing position.

75 Other forms of construction to swing the clamp tape or band 21 to and from the work 80 may be utilized without departing from the spirit of the invention, and the device fills a need felt for a work holder to improve and speed up the ironing operations.

85 What I claim is:—

1. In a pressing machine, a frame, a buck, a head movable toward and from the buck, a work holder carried by the frame and including a pivoted carrier swingable forwardly and rearwardly and having spaced apart 90 members, a tape connecting the members, the front member being shaped to pass over the face of the buck and to clear the end of the buck when moved into and out of operative position, and means for automatically moving the carrier to move the tape toward and from the buck.

95 2. In a pressing machine, a frame, a buck carried by the frame, a head movable toward and from the buck, a work holder carried by the frame and pivoted below the buck and having upwardly extending arms diverging from its axis, the front arm having an upright portion arranged to clear the end of the buck during pivotal movement of the carrier and a horizontal portion extending in a horizontal plane over the face of the buck, and a work clamping member connecting the rear arm and the horizontal portion of the front arm, and means for moving said member toward and from the face of the buck when it is in position over the buck.

100 3. In a pressing machine, a frame, a buck, a head movable toward and from the frame, a work holder mounted on the frame comprising a carrier, a work clamping member carried by the carrier, means for moving the carrier into and out of a position contiguous with the face of the buck during the movement of the carrier, and a vertically movable support for the carrier, said support being 105 carried by the frame.

115 4. In a pressing machine, a frame, a buck, a head movable toward and from the buck, a work holder comprising a movable carrier, a work clamping member carried by the carrier, means for moving the carrier into and out of a position contiguous with the face of the buck during the movement of the carrier, and a lever pivoted to the frame to move in 120 125 130

a vertical plane, the carrier being pivoted to the lever, the lever being movable to move the carrier to bring the work clamping member downwardly and upwardly into and out of engagement with the work on the buck.

5. In a pressing machine, a frame, a buck, a head movable toward and from the frame, a work holder comprising a movable carrier, a work clamping member carried by the carrier and movable into and out of a position over the face of the buck during the movement of the carrier, a vertically movable support for the carrier, said support being carried by the frame, means tending to move the

10 support upwardly, a cam on the frame acting to move the support downwardly, and a cam follower on the carrier coacting with the cam.

6. In a pressing machine, the combination of a frame, a buck, a head movable toward and from the buck, a work holder movably mounted on the frame and including a carrier, and a work engaging member, the carrier being movable to carry said member across the buck into and out of position over

25 the face of the buck, and means for moving said member toward the face of the buck to clamp the work thereon after said member is moved to a position over the buck.

7. In a pressing machine, the combination of a frame, a buck, a head movable toward and from the buck, and a work holder movably mounted on the frame to move forwardly and rearwardly of the frame and also vertically and including a carrier having spaced

35 apart front and rear arms, and a work engaging member connecting the arms, the front arm being shaped to pass over the face of the buck and to clear the end of the buck when moved into and out of operative position and

40 means for causing the work holder to move vertically when in position over the buck.

8. In a pressing machine, the combination of a frame, a buck, a head movable toward and from the buck, and a work holder movably mounted on the frame and including a carrier and a work engaging member, the carrier being movable to carry said member over the buck into and out of position over the face thereof, means for moving the carrier to move

50

said member toward and from the face of the buck to clamp the work thereon after said member is moved to said position over the buck, said means including a cam on the frame and a follower on the carrier coacting with the cam during the forward and rearward movement of the carrier.

9. A work holder for a pressing machine having a pressing buck comprising a work

60 clamping member and a movable carrier upon which the work clamping member is mounted, said carrier and work clamping member having vertical movement relatively to the buck to clamp a piece of work thereon, and also having a swinging movement

to carry the clamping member crosswise the buck between the ends thereof.

10. A work holder for a pressing machine having a pressing buck and head, and comprising a work clamping tape, a movable carrier upon which the work clamping tape is carried, and means to afford said movable carrier and work clamping tape movement relatively to the buck to clamp a piece of work thereon, said clamping member being disposed substantially crosswise and between the ends of the buck and between the engaged pressing surfaces of the head and buck when in final clamping position.

11. A work holder for a pressing machine having a pressing buck comprising a work clamping tape, a carrier upon which the work clamping tape is carried, said carrier being pivoted for movement into and out of position contiguous with the face of the buck and the pivot being so arranged as to give said carrier and work clamping tape a downward movement relatively to the buck to clamp a piece of work thereon.

12. In a garment or ironing machine, a coacting press head and buck, and a work holder to clamp work in the machine comprising, a clamping band, a swingable carrier frame under the clamping band and to which the clamping band has its ends attached, and pivot means on which the carrier frame is operatively mounted to swing the carrier frame under the buck and the clamping band over the buck to and from the work thereon.

13. In a garment or ironing machine, a coacting press head and buck, and a work holder to clamp work in the machine comprising, a swingable carrier frame, said carrier frame having spaced portions one of which swings into operative position in front of the buck and the other at the rear thereof, a clamping band above the carrier frame having its ends anchored to the spaced carrier frame portions, and pivot means on which the carrier frame is operatively mounted to swing said carrier frame under the buck and to swing the clamping band over and substantially crosswise of the buck to clamp the work thereon.

14. In a garment or ironing machine, a coacting press head and buck, and a work holder to clamp work in the machine comprising, a clamping member, a swingable carrier frame including upstanding spaced arms one of which is to the rear and the other in front of the buck, the clamping member being attached to the upper ends of the spaced arms and swingable therewith, and pivot means below the buck and on which the carrier frame is mounted to swing the clamping member to and from a crosswise position over the buck and the work thereon.

15. In an ironing press having coacting jaws, and a work clamp to hold in smooth condition the material to be ironed, comprising

ing a clamping tape, a carrier frame including spaced end portions to which the ends of the clamping tape are secured; and compound-motion pivot means operatively mounting the work clamp on the press to swing the clamping tape over and clear of the work, into position crosswise of the jaw, and the carrier frame under the jaw, and to afford up and down motion of the carrier frame to engage and release the material after such crosswise position is reached.

16. In an ironing press, a coacting press head and buck having engaging ironing surfaces, and a clamp to hold the work in the press, comprising a movable carrier device, a work-clamp member operative between the head and buck and mounted on the movable carrier device; and mounting means operatively supporting the carrier device and its work-clamp member in working position on the press and away from the buck, to move said work-clamp member into position crosswise of the buck under the head while the head is up, and to clamp the work in smooth condition before the head descends to the buck.

17. In an ironing press, a coacting press head and buck, operating means to actuate the head to open and close the press, a work holder to clamp the tail of a shirt on the buck comprising a clamping member, a swingable carrier on which the clamping member is mounted to move said clamping member to the rear of the buck and back out of the way of the operator when the clamping member is not in use, and pivot means operatively mounting the swingable carrier on the press for imparting a back and forth motion to the clamping member above the work to avoid displacing the smooth lay of the work and for up and down motion to release and engage the work after the clamping member has reached a crosswise position over the buck.

18. In a garment ironing machine, a coacting press head and buck, and a work holder to clamp work onto the buck comprising a bowed flexible clamping band, a swingable carrier frame having a portion movable into position at the front edge of the buck and another portion movable into position at the rear edge of the buck, the flexible clamping band having its ends attached to the spaced portions with the center of said band bowed upwardly to arch over the buck, and pivot means on which the carrier frame is operatively mounted to swing the carrier frame under the buck and the bowed flexible clamping band over the buck from one end thereof.

19. In testimony whereof, I have hereunto signed my name, at Syracuse, in the county of Onondaga, and State of New York, this 16th day of April, 1926.

ALBERT B. CLISSON.
